LOCK FOR DOORS, DRAWERS, OR THE LIKE

Filed Sept. 20, 1928

UNITED STATES PATENT OFFICE

TIMOTHY SMITH, OF MORNINGTON, DUNEDIN, NEW ZEALAND

LOCK FOR DOORS, DRAWERS, OR THE LIKE

Application filed September 20, 1928. Serial No. 307,294.

This invention relates to locks, and more particularly to locks of the kind commonly known as rim, and mortice locks.

The present invention has for its object 5 certain improvements in the structural features of such locks, for instance, dispensing with the special locking bolt, the latch bolt being adapted to be locked. By means of this construction the size of the lock may be 10 reduced without impairing its efficiency. This applies more particularly to the mortice lock, in which the few operative parts are so compactly arranged that the lock may be 15 made of a thickness substantially less than any of the locks of this type hitherto constructed.

According to the present invention, the lock comprises a metal case and a latch bolt slidably operative therein. The inner portion of 20 the latch bolt resembles somewhat an outline of the letter P horizontally disposed, having a U shaped orifice therein, the orifice extending to a transverse strip provided at the end of, and projecting above the plane of the latch bolt.

The cam for shifting the latch bolt inwardly, is formed with a round boss adapted to engage in the U shaped orifice hereinbefore mentioned; this boss is provided with a projection on each side and in alignment, the outer edge of the projections abut on the inner edge of the transverse strip at the inner end of the latch bolt member. The ends of the cam boss are reduced in diameter for pivotally mounting the cam in a circular orifice provided in the metal case and the detachable cover thereof.

The cam is formed with a suitably shaped hole therethrough to receive a spindle, on which is mounted a handle or handles, by means of which the cam may be slightly rotated displacing the latch bolt member inwardly against the resistance of a spring.

The locking mechanism comprises a locking plate eccentrically mounted to rock on a pin extending between the front and rear plates of the lock case. The locking plate is formed with a projection against which the upper part of one leaf, of a substantially V-shaped spring, abuts. There are also other

projections on the locking plate, one to prevent it from being given an undue angular displacement, and the other to engage in a notch formed in the edge of the latch bolt member.

A suitably shaped orifice is provided in the locking plate, to permit of the key when inserted in the keyhole, and turned, to give the locking plate a slight angular displacement, moving the projection out of, or into engagement with the notch in the edge of the latch bolt member.

The spring hereinbefore mentioned, is pivoted on a pin secured in the lock case, the outer portion of the one leaf abutting on a stop or projection on the locking plate, and the outer portion of the other leaf abutting on a shoulder formed by the reduced thickness of the latch bolt inside the lock case.

But in order that the invention may be 70 better understood, drawings are appended illustrating the invention, wherein similar parts are designated by similar reference numbers throughout the several views, in which:—

Figure 1 shows a plan of a rim lock embodying the invention with a portion of the cover plate removed.

Figure 2 shows a plan of the rim lock looking from the front.

Figure 3 shows an end view of Figure 1.

Figure 4 shows an inverted plan of the locking plate.

Figure 5 shows a plan of the latch bolt member.

Figure 6 shows an edge view of Figure 5.

Figure 7 shows a plan of a mortice lock embodying the invention with a portion of the cover plate removed.

Figure 8 shows a plan, and Figure 9 a side view of the latch bolt member of the mortice lock.

Figure 10 shows an end view of Figure 7.

Figure 11 shows an inverted plan of the locking plate of the mortice lock.

Referring to the accompanying drawings, 1 indicates the lock case and 2 the rim or flange thereof, 8 is an overhanging extension of the end plate 6, and 7 are holes (preferably countersunk) for securing the lock to 100

the door by means of screws. The detachable cover plate 4 is formed with a projection or 5 projections, which engage in the slot or slots 6 provided in the sides, and in the end plate 6, of the lock case 1. The free end of the detachable cover plate 4, may be secured to the rim or flange 2, by the threaded screw 3.

The latch bolt member 9 rearwardly of the catch is formed of a thickness less than that of the catch, providing a shoulder 10 for one 10 leaf 13 of the spring 12, to abut against.

The contour of the latch bolt member 9, resembles somewhat the outline of the letter P horizontally disposed, as at 15, provided 15 with a U shaped orifice 14 therein. The outer end of the orifice 14 is closed by a transverse strip 11, the strip projecting beyond one face of the part 9a of the latch bolt member 9.

The cam is formed with a pair of oppositely 20 disposed wings 17. The outer edges 17a, of the wings, abut against the inside edge of the transverse strip 11 of the bolt member 9. The boss 16 of the cam extends through the U shaped orifice 14 of the bolt member and 25 its ends are reduced in diameter, as at 18, and are mounted to rock in round orifices 18a formed in the detachable cover 4 and in the front plate of the lock case 1, respectively.

For shifting the latch bolt 9 inwardly, a 30 square hole 19 is provided in the boss 16, through which a spindle of corresponding cross section (not shown) may extend, one end of said spindle being provided with a suitable handle (not shown). As the edge 35 17a of the cam abuts against the inside edge of the transverse strip 11, any turning movement of the handle will move the latch bolt member 9 inwardly against the resistance of the leaf 13, of the spring 12.

The locking mechanism comprises a locking 40 plate 20, provided with an eccentric opening 21b to receive a pin 21 carried by the front plate of the lock case 1.

The locking plate 20 has a key receiving 45 orifice 22 therein opposite the key-holes 23 in the front and rear plates of the lock case, so that when a key is inserted through said key-holes into said orifice and turned, it engages with one of the sides of the orifice 22, thus rocking the plate 20 on the pin 21 to 50 move a lug 24 carried by said plate into or out of engagement with the notch 25 in the lower edge of the latch bolt member 9.

It is obvious, that, when the locking plate 55 20 is given an angular displacement by means of the key when the key is turned in the orifice 22 in an anti-clockwise direction, the stop 24 will be moved out of engagement with the notch 25, and, when the key is turned in a clockwise direction, the stop 24 will engage in the notch 25, locking the latch bolt member 9 against displacement in an inward direction.

The plate 20 is held in position with its 55 lug 24 in engagement or out of engagement

with notch 25 of the bolt 9 by the other leaf 12a of the two leaf spring 12, which is pivotally mounted on the pin 12b in the lock case 1, the other leaf 13 of which holds the latch bolt member 9 outwardly, unless slidably moved inwardly by slightly rotating the handle operating the cam. The other leaf 12a has its free end abutting against one edge of a lateral projection 26 on the locking plate 20 when the lug 24 of said plate is in engagement with the notch 25 of the latch bolt 9 or against the opposite edge of said projection 26 when said lug 24 is out of engagement with said notch 25 and thus serves to hold the plate 20 in either locking or unlocked position.

A projection 27 is formed or provided on the locking plate 20, the toe, or toes 32, when there are two projections, as shown in Figure 11, abutting against the inner face of the 85 lock case 1. The plate 20 has a projection 27 extending laterally from its edge opposite the lug 24, as shown in Figures 1 and 4, which projection, when the plate 20 is rocked to unlocking position, bears against the lower 90 edge of the bolt 9, thus preventing the plate 20 from being rocked too far in that direction.

Referring to Figure 1 of the drawings, it will be seen that the orifice 22, in the locking plate 20, is formed substantially as a parallelogram, the corners being rounded. This shaped orifice adapts the rim form of lock for either right or left hand use.

Referring to Figure 7 of the drawings, which shows a mortice type of lock, parts 100 similar to the operative parts hereinbefore described in connection with the rim lock are provided. In this type provision is made for reversal of the outer part or catch of the latch bolt 9, in order to adapt the lock for 105 either right or left hand use. This is accomplished by forming in each side of the catch part of the bolt 9, at the inner end of said catch part, a depression of a depth equivalent to the thickness 9a of the inner part, so that 110 the forward end of the latter part may be seated in either of said depressions and be secured therein by a screw 29.

The detachable cover plate 4 may be formed with a pointed projection 30, so that, when the lock is disposed in a recess formed in the door, a blow may be delivered to the forward end of the lock case 1 to cause the pointed projection 30 to be driven into the wood to hold the lock anchored at its inner end.

The toe or toes 32, of the projection or projections 27, on the locking plate 20 (Figures 7 and 11) bear against the inner face of the lock case, and in order to prevent the locking plate 20 from lifting when being angularly displaced, a pin or projection 31 is provided in the cover 4, with its inner end engaging with the face of the said locking plate 20.

It will be understood that suitable wards

may be provided in the lock, and that the key may be formed to fit the construction of the wards.

Having thus fully described my invention, 5 what I claim as new and desire to secure by Letters Patent is:—

1. A lock comprising a casing having an opening in its forward end and a key-hole in each of its sides, a bolt longitudinally 10 shiftable in said casing with its forward end normally projecting through said opening, a plate mounted to rock in said casing on an eccentric axis and having a key-receiving opening opposite said key-holes, said bolt and plate having means to interengage and 15 secure said bolt against movement when the plate is rocked in one direction and to disengage and release said bolt when said plate is rocked in the opposite direction, said plate also having a member extending laterally 20 therefrom to engage one edge of the bolt and limit the movement of the plate when said plate is rocked in one direction, a single spring in constant engagement with said bolt 25 and said plate, said spring urging said bolt forwardly and holding the interengaging means between said bolt and plate either in engaging or disengaging position, and means for longitudinally shifting said bolt.

2. A lock, comprising a casing having an opening in its forward end and including front and rear plates each having a keyhole; a bolt including a nose normally projecting through said opening and a portion of a thickness less than the space between said plates, 30 said portion having a notch in its lower edge and being longitudinally shiftable in said casing with one of its faces spaced from one of said plates; a pin extending between said plates and on which the lower edge of the latter portion of the bolt is slidable; a locking plate mounted to rock on said pin between the last-named portion of said bolt 35 and the last-named plate, said locking plate having a key-receiving opening opposite said keyholes and a lug movable into the notch of said bolt to secure the bolt against movement when said locking plate is rocked in one direction and movable out of said notch to release the bolt when said locking plate is rocked in the opposite direction, said locking plate also having a projection extending laterally therefrom; and a substantially V-shaped spring having one arm bearing 40 against the nose of said bolt to urge said bolt forwardly and its other end bearing against the projection of the locking plate to hold the locking plate positioned with its lug either in or out of the notch of the bolt.

60 In testimony whereof, I have signed my name to this specification at Dunedin this 20th day of August, 1928.

TIMOTHY SMITH.
